ARTIFICIAL MOLAR TEETH

Ross O. Dickson, Mexico City, Mexico

Application August 8, 1947, Serial No. 767,561

1 Claim. (Cl. 32—8)

1

This invention relates to improvements in artificial teeth (bicuspids and molars), and particularly concerns the disposition of the occlusal surfaces in reference to the cusps, bearing surfaces, spillways, cutting edges, and ridges.

Artificial teeth at present in use may be roughly divided into two classes, the anatomical, simulating natural teeth, and the mechanical, having occlusal surfaces provided with depressions or cavities of various shapes and arrangements. The anatomical teeth have on their occlusal surfaces irregular shaped, rounded cusps separated by fissures and are so arranged that the cusps on an upper tooth seat in the fissures in the meeting occlusal surface of a complementary lower tooth and the cusps on the lower tooth seat in the fissures in the corresponding upper tooth. This provides an extremely efficient cutting and grinding structure which, in the case of natural teeth, has no particular disadvantage. In the case of artificial teeth however, the interlocking of the cusps and complementary fissures of the upper and lower teeth tends to dislodge the dentures if the lower jaw or mandible is moved laterally relative to the upper jaw, as is necessary to produce a grinding action to properly masticate food. This causes the wearers of artificial teeth of the anatomical type to restrict the movements of the upper and lower jaw to a simple chopping movement toward and away from each other. This is highly undesirable as it results in inadequate mastication of food and strain on the facial muscles.

In order to avoid this difficulty dentists have devised the so-called mechanical or cuspless type of teeth having substantially planar occlusal surfaces which can be moved laterally relative to each other while in contact with sufficient ease that the dentures are not dislodged.

Obviously planar occlusal surfaces would have very little grinding or masticating efficiency so the designers of this type of teeth have provided the planar occlusal surfaces with recesses or depressions in the attempt to increase their masticating efficiency. Such recesses have been provided in the form of long, narrow, substantially parallel grooves, in some cases intersected by cross grooves, but such grooves have very little effect as they soon become clogged with partly masticated food which they are unable to discharge. Another attempt has resulted in the provision of a groove around the occlusal surface within the margin of such surface and a notch leading from this groove to the lingual side of the tooth. Such a groove also clogs and this

2

construction has likewise been found too inefficient for satisfactory use. Still another attempt has resulted in the provision of spaced apart depressions of geometric, usually triangular, shape in the occlusal surfaces, such recesses having inclined bottom walls making them V-shaped in cross section. Such grooves or recesses also quickly fill up with compacted food as they are not cleaned by complementary cusps as in the case of natural or artificial teeth.

Both the cusped or anatomical teeth and the cuspless or mechanical teeth thus have serious disadvantages in use. It is conceived however, that teeth having the easy sliding facility of the mechanical type and, at the same time, the self-cleaning facility of the anatomical type would substantially overcome the major difficulties of the two present types or classes of artificial teeth. Such a tooth may be designated a flat cusp tooth.

For the purposes of the present description a cusp may be defined as a projection on the occlusal surface of a tooth, such projection being confined to one portion of the tooth, having an area which is a fraction, less than $\frac{1}{3}$, of the area of the occlusal surface, and is surrounded by steep sides and separated from other cusps of the same tooth by fissures or grooves.

At the time of eruption, natural teeth have sharply pointed cusps but during use these points wear down to a rounded shape and finally to substantially flat surfaces and the cusps may then be designated as flat cusps. Even such flat cusps will interlock to a limited extent in the corresponding fissures or depressions but, because of their shape and the shape of the corresponding fissures the self-cleaning facility of even worn natural teeth is maintained.

The present invention contemplates the provision of artificial teeth having the fissures or depressions, also referred to as canals or spillways, so shaped as to provide an adequate self-cleaning action and having the cusps flattened and shaped, and in some cases interconnected by ridges, to substantially eliminate the interlocking of the cusps in the associated fissures or depressions. In this case an adequate and efficient grinding action is obtained between the cusps and ridges of complementary upper and lower teeth and an effective cutting action is obtained from the shearing effect between the edges of the cusps of the complementary upper and lower teeth.

A principal object of the present invention is thus to provide a set of artificial teeth having

substantially as effective self-cleaning action as natural teeth while avoiding the interlocking of the cusps and fissures which is normal in natural teeth but tends to dislodge the dentures if present in artificial teeth.

It is further among the objects of the present invention to provide an artificial tooth construction in which the cusps are flat, permitting the free movement of the mandible in all directions, anterior, posterior, or lateral, without the cusps interfering, as in present constructions of anatomical artificial teeth. Each upper molar tooth has spaced-apart cusps and an angular, longitudinally extending ridge which passes lingually, buccally and buccally lingually over spaced-apart cusps and a longitudinally extending, straight ridge of the complementary inferior molar so that the edges of the cusps and ridges shear the food. The masticated food escapes through the depressions or food canals buccally and lingually, being moved outwardly of these canals by the relative movement of the cusps of occluded upper and lower teeth, thus permitting the cutting edges to contact more efficiently. In the present invention, the flat cusps become bearing surfaces and are separated by the canals or spillways which receive the food after being cut or ground and open freely to the sides of the teeth. As the food is caught in the grooves of the superior teeth, it is cut by the sharp edges of the cusps and central ridges of the inferior teeth, as the latter pass the sharp margins of the superior grooves, thus cutting, grinding and disposing of the food more efficiently and maintaining the occlusal surfaces of the teeth free of compacted food.

The foregoing and other objects and features of the invention will be made fully apparent to those skilled in the art from a consideration of the following detailed description taken in conjunction with the accompanying drawings, in which:

Figure 1 is an elevational view from the buccal side of the teeth of the present invention with the teeth in occlusion.

Figure 2 is an elevational view of the teeth of Figure 1 from the lingual side thereof.

Figure 3 represents a bottom plan view of an upper molar constructed in accordance with this invention.

Figure 4 represents a plan view of a lower molar.

Figure 5 is a cross-sectional view on an enlarged scale taken on the line V—V of Figure 1.

Figure 6 represents a plan view of a lower bicuspid.

Figure 7 is a bottom plan view of an upper bicuspid.

Figure 8 is a view corresponding to Figure 3 of a slightly modified form of the upper molar.

Figure 9 is a view corresponding to Figure 4 of a slightly modified form of the lower molar.

Referring to the drawings, and first to Figures 1 and 2 thereof, the teeth there shown comprise an upper first molar 1, an upper second molar 2, an upper first bicuspid 3, an upper second bicuspid 4, a lower first molar 5, a lower second molar 6, a lower first bicuspid 7, and a lower second bicuspid 8. The arrow D points to the distal and the arrow M points toward the mesial ends of the dentures.

It will be observed from these figures that all of said teeth have flat, occlusal surfaces, and that the teeth are free from projections extending beyond such flat or plane surfaces. The

bearing surfaces, as will hereinafter be disclosed in detail, comprise the flat tops of cusps, and the flat tops of cutting ridges connecting certain of the cusps, said cusps having intervening depressions or canals opening buccally and lingually to the sides of the teeth, the buccal side appearing in Figure 1, and the lingual in Figure 2. The areas and disposition of the occlusal surfaces relative to the canals and spillways are such that the cusps cannot project into the depressions in any position of the mandible.

Throughout the drawings, reference numeral 10 designates the buccal or outer, 11 the lingual or inner, 12 the mesial or front, and 13 the distal or rear faces of the teeth.

In Figure 3, the upper molar there shown is provided with a distal lingual flat cusp or bearing surface 14, a distal buccal cusp 15, a mesial buccal cusp 16, a mesial lingual cusp 17, a depression or food canal 18 between the cusps 14 and 17 leading to the lingual face, a canal 19 between the cusps 15 and 16 to the buccal face, a canal 20 between the cusps 14 and 15 leading to the distal face, and a cutting ridge 21 connecting cusps 14 and 17. The cutting ridge 21 extends inwardly toward the center line of the tooth presenting a generally angular or V-shaped formation and the canal 20 extends adjacent and parallel with the sides of the V opposite the canal 18. In this figure, as in Figures 7 and 8, the central line of the upper teeth is indicated by X1.

In Figure 4, the lower molar 5 there shown is provided with a flat mesial-lingual cusp 14a, and a mesial buccal cusp 15a, a distal buccal cusp 16a, a distal lingual cusp 17a, a food canal 18a between the cusps 14a and 17a leading to the lingual face of the tooth, a food canal 19a between the cusps 15a and 16a leading to the buccal face. A central ridge 20a extends from a location between the cusps 14a and 15a longitudinally of the tooth, between the cusps 16a and 17a and to the distal or rear face of the tooth. A short canal 27 between cusps 16a and the distal end portion of ridge 20a opens to the distal face, and a short canal 29 between the cusps 17a and the ridge also opens to the distal face of the tooth, and a distal wedge-shaped central cusp 22a. In this figure and in Figures 6 and 9, the line X2 indicates the central line of the teeth.

In Figure 5, the upper molar 1 is shown in normal relation to the lower molar 5. The cusps 14 and 15 of the upper are in occlusion, respectively, with the cusps 14a and 15a of the lower, the distal portions of the superior cusps extending over the canals 18a and 19a, respectively, of the inferior molar. The longitudinal canal 20 of the superior overlies the central cutting ridge 20a of the inferior, and it will be seen that on relative movement of the teeth in any direction, the same remaining occluded, a shearing action will be obtained. It will also be noted that the food canals are of V-shaped cross-section and open directly to the sides of the teeth so the masticated food will continuously pass outwardly of the teeth through these canals and will not pack in the canals or depressions. The self-cleaning facility of the teeth is thus maintained.

The construction of the lower and upper bicuspids as shown in Figures 6 and 7, respectively, is analogous to that of the lower and upper molars of Figures 4 and 3, respectively; in that the cusps are all flat, the occlusal surfaces lying in a single plane, the cusps and cutting ridges being

flush with each other and divided in the central line by longitudinal grooves in the superiors which function over the central cutting ridges of the inferiors. Referring to Figure 6, the lower bicuspid shown is provided with a food canal 23a, which runs generally parallel with the central ridge 26a. The lingual cusp 24a and the buccal cusp 25a are both flat with their surfaces lying in the same plane. A short distal canal to the buccal side of the tooth is provided at 27a, and a depression 28a on the first inferior bicuspid functions as a spillway for the second bicuspid.

In Figure 7, the upper bicuspid corresponding to the lower of Figure 6 is shown and comprises a lingual cusp 24, a buccal cusp 25, and a longitudinal canal 23 between the two cusps.

In the slightly modified form shown in Figure 8, the ridge 21b connects the cusps 14b and 16b rather than the cusps corresponding to 14 and 16 of the form shown in Figure 3. This ridge thus interrupts the canal 20b. Otherwise correspondence between the parts numbered 14b, 15b, and so forth, and the parts numbered 14, 15, and so forth, of the previously-described forms will be apparent. The lower molar shown in Figure 9 corresponds to that shown in Figure 4, except that the two spillways 18c are provided to the lingual side of the tooth. Otherwise, the correspondence between the parts numbered 14c, 15c, and so forth, and the parts numbered 14a, 15a, and so forth, of Figure 4, will be apparent.

It will be noted that in all the occlusal surfaces of these molar teeth, the cusps and cutting ridges are flush one with another, and that the cutting margins of the cusps and ridges are so arranged that the opposing margins pass over them with a shearing or scissor-cutting action as they pass each other with any movement of the mandible forward, backward, laterally, or rotary, the food being dropped in the spillways between the teeth and in the teeth for disposal.

While there have been herein described certain

preferred embodiments of the invention, other embodiments within the scope of the appended claims will be fully apparent to those skilled in the art from a consideration of the forms shown and the teachings thereof.

I claim:

- In a group of artificial teeth including complementary lower and upper teeth having meeting occlusal surfaces of planar formation, a lower tooth having in its occlusal surface depressions opening to the sides of said tooth and defining four flat topped cusps respectively disposed at the mesial-lingual, distal-lingual, mesial-buccal and distal-buccal corners of the tooth and a narrow ridge extending from a location between the mesial lingual and mesial buccal cusps, between the distal lingual and distal buccal cusps to the distal end of the tooth, and a complementary upper tooth having in its occlusal surface depressions opening to the sides of the tooth defining four flat topped cusps respectively disposed at the mesial-lingual, distal-lingual, mesial-buccal and distal-buccal corners of the tooth, and a narrow ridge extending from the mesial-lingual cusps to a location adjacent the center of the tooth and from such location to the distal-lingual cusps, and providing a groove between said ridge and the mesial-buccal and distal-buccal cusps.
